UNITED STATES PATENT OFFICE

WILLET E. STARK, OF EAST CLEVELAND, OHIO, ASSIGNOR TO THE BRYANT HEATER & MFG. CO., OF CLEVELAND, OHIO, A CORPORATION OF OHIO

GAS BURNER

Application filed December 19, 1927. Serial No. 241,012.

This invention relates to burners and more particularly to gas burners for heating systems, and has for its primary object to provide a burner which is efficient in its operation and a decided improvement over those types now employed.

A further object of the invention is to eliminate some of the objections inherent in the present types of gas burners as will be more fully pointed out.

Referring to the drawing:

Fig. 1 is a fragmentary side elevational view of a boiler partly in section embodying the invention.

Fig. 2 is a fragmentary longitudinal sectional view of the mixer for the burners on an enlarged scale.

In the drawing I have illustrated part of the boiler which is of customary construction and comprises a base 10, usually of cast iron, and supporting upon its upper portion a plurality of boiler sections 11, one of which is here shown.

The base 10 near its lower inner portion has inwardly projecting members or lugs 12, which support a perforated plate 13, and the space between the plate and the lower ends of the boiler sections 11 is usually termed the combustion chamber.

A plurality of burners 14, only one of which is here shown, are disposed within the combustion chamber for the purpose of supplying the heat for the water within the boiler sections 11, and each of the burners 14 is connected to a common manifold 15 communicating with a suitable gas supply line. The burners 14 are individually controlled by hand operated valves 16, so that the quantity of gas being fed to the burners can be regulated as desired. It is customary to provide a mixer or entrance for the primary air supply, which is usually disposed in the gas line connecting the burners 14 to the supply of gas in the manifold 15, and usually located outside of the combustion chamber. This mixer or air entrance permits a predetermined quantity of air to be drawn in and the same is thoroughly mixed with the gas before passing to the burner, to thereby produce a suitable combustible mixture. Such

a location of the mixer, however, results in an objectionable condition inherent in systems of this character which will be briefly explained.

When gas burners, such as the one just described, are employed with a gas that is high in hydrogen, thus making it burn very quickly, there is a tendency for quite a loud explosion to be produced when the burners are extinguished. This is particularly pronounced in home heating boilers and furnaces and results from having the burners in the combustion chamber while the mixer or air inlet is located outside of the combustion chamber. The result is that the exits from the burners or ports as they are termed, are subject to a pressure lower than atmospheric, due to the draft or pull of the chimney, while the entrance to the primary air mixer is subject to atmospheric pressure, 70. With this arrangement, when the gas supply is cut off, air is drawn from outside the combustion chamber (atmospheric) through the primary air entrance, owing to the slight draft that exists inside the combustion chamber. This air mixes with the air and gas mixture already in the mixer, mixer tube and burner, making it more explosive. The difference in pressures between the inside and outside of the combustion chamber pulls this 75 increasingly thinner mixture out of the burners where it continues to burn at the burner ports. When the mixture gets thin enough and explosive enough, its rate of propagation becomes higher than the rate at which it is issuing from the burner ports, with the result that the flame passes back into the burner, and the remaining gas burns instantly with a loud noise. If this takes place in a boiler or furnace, the noise is very pronounced and is transmitted through the entire system making it very annoying. This trouble is experienced principally with gas high in hydrogen or the usual manufactured gas and the entire action takes place in but a few seconds.

To overcome the objections just referred to in systems of the character described, it is my intention to locate the mixer or entrance for the air within the combustion chamber 100

and it will be found that the explosive action is eliminated. The reason for this is that the air pressures at the burner ports and at the primary air entrance are equal. When the 5 gas flow is cut off a static condition is established and there can be no flow of the mixture in either direction. The rate of flame propagation of the normal mixture remaining in the burners and the mixer tube is so 10 low that the heat is abstracted fast enough by the cast iron of the burner body to thereby prevent the flame from passing back through the ports and igniting the residual gas in the burners and mixer tubes. The flame, therefore dies away and there is no explosion. 15

A preferred arrangement of the device is illustrated in the accompanying drawing, but it should be understood that the invention is applicable to various types of heating systems. 20

A mixer 17 is located within the combustion chamber and suitably connected in the gas supply line between the manifold 15 and the burners 14, providing a suitable entrance 25 for the air adapted to be mixed with the gas to provide a mixture of suitable combustible properties.

The mixer 17 comprises an enlarged cylindrical portion 18 formed integral with the 30 end of the mixer tube 19, and has a concentric tubular member 20 supported by an integral web, the latter having a plurality of apertures 21 extending therethrough for the passage of air into the mixer tube. The forward 35 or outer end of the member 20 is exteriorly screw-threaded to receive an adjustable member 22 which has an enlarged end 23 of substantially the same diameter as the enlarged portion 18 and cooperates with the latter to 40 control the quantity of air which passes into the mixer tube 19, that is, a less quantity of air is admitted when the adjustable member 22 is advanced toward the enlarged portion 18 and a greater quantity of air is admitted 45 to the mixer tube 19 when the adjustable member 22 is moved away from the enlarged portion 18, by varying the space or air passage between the enlarged portion 18 and the enlarged end 23. 50

The adjustable member 22 has formed at its forward end a nut 24 for moving the former along the tubular member 20, and is positioned outside of the combustion chamber so that adjustment is afforded from the outside of the boiler. The adjustable member 22 preferably extends through an opening 25 provided in the front portion of the base 10, as shown in Figs. 1 and 2. 55

The pipe 26 which communicates with the manifold 15 and through which the gas is supplied to the burners, has its free end extending through the adjustable member 22. The outer surface is provided with screw-threads and supports a tubular extension 27 60 which extends within the tubular member 20

and is interiorly screw-threaded to receive a plug 28 provided with a reduced gas passageway 29.

The gas admitted through the passage 29 commingles with the air admitted through 70 the apertures 21 and the two thoroughly mix in the mixer tube 19 in the desired proportions to produce an efficient combustible fuel.

Having thus described my invention, I 75 claim:

In a gas burning apparatus, the combination of a combustion chamber, a burner therein, an air and fuel mixing device communicating with the burner, means for delivering fuel to said device, and adjustable means disposed partially within and partially without the combustion chamber and adjustable from outside the chamber for regulating the primary air supplied to said device and for causing said air to be supplied from inside 85 the combustion chamber at a reduced pressure.

In testimony whereof, I hereunto affix my signature.
